UNITED STATES PATENT OFFICE

SAMUEL E. BOUCHARD, OF ROCHESTER, NEW YORK, ASSIGNOR TO BAUSCH & LOMB
OPTICAL COMPANY, OF ROCHESTER, NEW YORK, A CORPORATION OF NEW YORK

DESIGN FOR A SPECTACLE FRAME

Application filed September 26, 1931. Serial No. 41,229. Term of patent 14 years.

To all whom it may concern:

Be it known that I, SAMUEL E. BOUCHARD, a citizen of the United States and a resident of Rochester, county of Monroe and State of New York, have invented a new, original, and ornamental Design for a Spectacle Frame, of which the following is a specification, reference being had to the accompanying drawings, forming a part hereof.

Fig. 1 is a perspective view of a spectacle frame embodying my new design.

Fig. 2 is an enlarged plan view of a fragment of the eye wire of the spectacle frame.

Fig. 3 is a sectional view taken on line 3—3 of Fig. 2.

I claim:

The ornamental design for a spectacle frame substantially as shown.

SAMUEL E. BOUCHARD.
